UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

STOP MOTION FOR CARD-TABULATING MACHINES.

Application filed September 13, 1917. Serial No. 191,155.

To all whom it may concern:

Be it known that I, WILLIAM W. LASKER, a citizen of the United States, residing in borough of Brooklyn, in the county of 5 Kings, city and State of New York, have invented certain new and useful Improvements in Stop Motions for Card-Tabulating Machines, of which the following is a specification.

10 The object of my invention is to provide a new and improved stop motion mechanism for use in card-tabulating machines, by the use of which when certain series of tabulating cards have passed through the tabulating card machine, and the last card of each 15 of such individual series passes through the machine the same will be automatically stopped, and be prevented from further operation and recording until a new series of 20 cards is inserted in the machine.

My invention herein disclosed described and claimed while not limited thereto relates primarily to tabulating machine mechanisms.

25 In machines of this character, it is frequently necessary that the feed stopping mechanism which stops the machine, upon a break in the series of cards should be located at some little distance from the card-feeding mechanism; it is also absolutely essential in order that the tabulation should be accurate that the tabulating mechanism of the recording machine should not over-rate or underrate the tabulation of the 30 cards; in other words it is absolutely essential in the proper manipulation of the machine that immediately upon the passage of the last card of each individual series, there should be no further actuation of the tabulating mechanism, until the insertion of another series of cards.

To such ends my invention consists primarily, and in broad substance, of an automatic stopping trip-mechanism which will 45 stop and lock the tabulating and recording mechanism against further movement immediately upon the passage of the last card of any given series or failure of an intermediate card of a series to be fed, thru 50 the tabulating mechanism; which tripping and stopping mechanism is preferably but not necessarily connected with the card-feeding mechanism of the tabulating machine by a flexible-connection, so as to save weight

and valuable working-space adjacent to the 55 tabulator and recorder.

My said invention is fully shown described and claimed, in the following specification, of which the accompanying drawings form a part; wherein similar letters or 60 numerals or references, designate like or equivalent parts throughout the several views, and in which:—

Fig. 1 is a top plan-view in perspective, and in detail of my improved tabulating 65 machine-stop mechanism.

Fig. 2 is an end view of such mechanism looking from the bottom of Fig. 1 in the direction of the arrow, taken partially in section substantially on the line 2—2 of such 70 Fig. 1.

Fig. 3 is a view in detail of the left hand portion of Fig. 2, showing the stopping and releasing mechanism in the releasing position. 75

Fig. 4 is a side view of the releasing mechanism and the connections looking toward the left of Fig. 1 taken on the line 4—4 of Fig. 1, showing such mechanism in the stopping position assumed by it immediately 80 after the last card has passed thru the tabulating and recording mechanism.

Fig. 5 is a view similar to Fig. 4, of the lower portion of the stopping-mechanism shown in Fig. 4, showing the position of the 85 parts when in the normal and non-stopping position; and

Fig. 6 is a view in detail of the card-feed and stopping mechanism shown in the upper right hand portion of Fig. 4, in the 90 stopping position, when in the non-stopping and card-feeding position.

Fig. 7 is a side elevation, shewing my stop mechanism applied to a tabulating machine. 95

Referring to the drawings:—

The reference letter A, designates a main-frame usually of substantially the shape shown in Fig. 1, having at one end a journal box 11, in which is revolvably mounted a 100 shaft 12, having the pulley or drive-wheel 13, driven by a motor 13'. The inner end of shaft 12, is journaled in an inner journal-box or housing 14, supported by a bracket 15, secured to the frame A, in which journal-box 105 or housing, is journaled a worm-gear wheel (not shown) mounted upon a revolvble-shaft 16 meshing with an endless screw

(not shown) carried by the shaft 12, by which said shaft 16 is rotated. And rigidly secured to or formed integral with the shaft 16, of the worm-wheel is a throw-lever 17, engageable with the end portion 18, of the reciprocating stop-plunger 19, rigidly secured to or formed integral with said end portion 18 and the like shaft 18'. The stop plunger 19 is provided with the annular peripheral screw-threaded shift-slot 20, in which works the end of the shift-screw 21, passing thru the side wall of the stop-journal slip-chamber E of the housing B, usually and preferably formed integral with the main gear-wheel 22 revolvably supported upon the journal shaft 23. The gear wheel 22 meshes with a gear-wheel (not shown) in connection with the tabulating and recording mechanism generally denoted by T, such as shown in applicant's Patent No. 1,388,271, dated August 23, 1921, which forms no part of this invention, the application of which invention, however, is not limited to that particular machine.

The stop-plunger 19 is secured in place in the slip-chamber E by the screw-threaded end-plug 24 thru which the outer end of the shaft 18 passes, while at the other end the shaft 18', passes out thru and is revolvably journaled in the wheel 22, and is provided at its outer end with the small gear-wheel 25, rigidly secured thereto. Concentrically mounted upon the shaft 18 between the stop plunger 19, and the wheel 22, is the helical or coil spring 26, one end of which fits into a journal-box or perforation 27, formed to receive it in the wheel 22 while the other like end fits in a like journal-box perforation, in the stop-journal or plunger 19; the tension of said spring 26 serving to normally keep the shaft 18, thrust outward as indicated in Fig. 2 in dotted lines so as to contact with the throw-lever 17 of the shaft 16; whereby it will be seen that the rotation from the top toward the front of Fig. 2, of such shaft 16, will by the contact of said lever 17, with the end-shaft 18, cause a rotation of the wheel 22 carrying with it the wheel 25, in the same direction, as clearly indicated by the arrow in Fig. 4.

Vibratorily supported upon the pivot-shaft 35, supported in the side-wall of the frame A, is the stop trip-lever 36, supported against side displacement in a slot 37, of a hollow supporting-stud 38, within which is a helical or coil-spring 39, normally pressing the outer free end of such vibrating trip-lever 36 upward. Immediately above the spring 39 the trip-lever 36 is provided with the segmental rack-gear 45, adapted when such trip-lever 36 is thrown upward to mesh with the gear-wheel 25 in such manner that the continued rotation of the wheel 22 will cause the rotation of such gear-wheel 25 and its shaft 18 (as clearly indicated by

the arrows in Figs. 2, 3, and 4) so as to, by the action of the stop plunger 19 upon the screw 21 draw back said stop plunger 19 and the shaft 18 against the tension of the spring 26 into the position shown in Fig. 3 so as to draw the outer end of the shaft 18 out of contact with the throw lever 17, carried by the shaft 16 and also to exert a positive braking action against the frame A; whereupon the rotation of the gear-wheel 22 will be instantaneously stopped.

The trip vibrating lever 36, is locked in place, in its lowered position shown in Fig. 5, by bell crank or detent lever 46, pivotally mounted on the pivot-screw 47 and normally pressed upward into the locking position shown in Fig. 5, by the spring 48 in the slotted socket stud 49.

On the other end of the trip-lever 36, and integraliy formed therewith is the lock-lug 50 having located in the space 51 the throw-pin 52 of the release lever 53, pivotally mounted on the stud shaft 54, adjacent to which is also pivotally mounted on the stud shaft 55 the bell-crank lock-lever 56, normally forced into the locking position shown in Fig. 4 by a helical or coil spring 57 secured at one end to the lock-lever 56; and at the other to the frame A. The lock-lever 56 is provided with the lower slide-face 56', which upon the movement of such lever rides up and down over the lower throw-pin 52', of lever 53 and ends at the top in a horizontal catch-surface 59, which engages with the lock-lug 50 when the vibrating rack-lever 36 is automatically thrown up into engagement with the release gear wheel 25 by the spring 39 as shown in Fig. 4; so as to lock such rack-lever 36 against accidental displacement.

Connecting this before mentioned release mechanism with the card sorting and tabulating machine, is any suitable mechanism for unlocking the trip-lever 36, whenever no tabulating card is in position under the tabulating mechanism.

The connecting mechanism connecting said tabulating and recording mechanism and my improved stop-mechanism therefor, may be of many and varied forms, but when, as is usually the case, the stop mechanism is located some distance from the card-sorting and tabulating card actuated mechanism, I prefer to use the mechanism shown, wherein the reference numeral 60 designates a hollow flexible-connecting coil of any suitable form such as braided or woven wire, or other suitable material, the upper end of which is secured to a suitable support 61, supported in any suitable manner upon the main-frame (not shown) of the card tabulating and recording machine, the lower end of which hollow coil is provided with a solid metallic sleeve 62, secured by screws 63, to the side wall of the frame A, all as clearly indicated

in Fig. 4. Through the flexible connecting coil 60, easily reciprocates a flexible-plunger 65, usually of highly tempered steel wire, the lower end of which is adapted when such wire 65, is forced downward to contact with the horizontal trip end-member 46', of the bell-crank lever 46, so as to force such bell-crank lever 46, against the tension of the spring 48, down into the unlocking position shown in Fig. 4, so as to release the triple-lever 36, and permit the same to be forced upward by the spring 39, with its rack 45 thrown into mesh with the release small gear-wheel 25, carried by the gear-wheel 22 (as shown in Fig. 4).

I have not deemed it essential herein to show the card feeding and tabulating mechanism in full, but only a slight portion thereof; but in the card tabulating machines of the particular form with which my improved stopping vehicle is designed to be used, the perforated cards designated by D, as shown in Fig. 3, are by suitable mechanism (not shown) fed from the front of said Fig. 6, toward the rear, over a supporting card-table or plate 67, and as each card comes into proper tabulating position upon said plate or table 67, tabulating-plungers (not shown) are forced through what perforations are in the particular card which is in position to have its data recorded, by the tabulating and recording mechanism machine; such recording and tabulating mechanism being put into recording and tabulating operation by such plungers, as are passed through perforations in the card.

Supported above the table or plate 67, is a vertical shaft 68 upon which reciprocates a slip-sleeve 69, carrying a stop-pin 70 passing through the plate 67, and the stud 71, formed integral with the slip-sleeve or journal 69, and also passing through and secured to a throw-lug 72 having rigidly secured therein a feeling device or detector plunger 73, in registry with a perforation in the card-plate table 67, which throw-lug 72 reciprocates up and down thru a journal bar 74, formed integral with or secured to the standard or shaft 68, and between the lugs 71 and 72 is interposed a spring 75 usually of the helical coil form shown.

As the slip sleeve 69, is lifted upward, at the same time (and by mechanism not shown and which forms no part of my present invention) the cards D are one by one automatically fed under the feeling device or detector plunger 73, and upon the downward movement of 69, such feeling device or detector plunger 73 is stopped from passing through the plate or card table 67, by impingement upon the card, as clearly indicated in Fig. 6; when however, the last card of any particular series has passed, and no card is in place beneath the plunger 73 (as indicated in Fig. 1 at the

top and right) such plunger 73 passes through the perforation in the card table 67, and carries with it the stop-pin 70, which impinges upon the top end of the reciprocating stop wire 65, and forces it down through 61, 60, and 62, upon the rear end 46' (Fig. 5.) of the bell-crank lock-lever 46, so as to force such lever down into the unlocking and releasing position shown in Fig. 4, against the tension of the spring 48, whereupon the spring 39 will throw lever 36, up into mesh with the gear wheel 25, and the continued rotation of the wheel 22 will draw out the shaft 18 against the tension of the spring 26 into the position shown in Fig. 3, into non-engagement with the throw-lever 17 rigidly secured to the shaft 18, whereupon the tabulating and recording mechanism will be instantaneously, stopped until such time as by the throwing upward by hand, (upon the insertion of the first of a new series of cards) of the lever 53, the vibrating segmental rack-lever 36 will be thrown downward against the pressure of the spring 39, into the running position shown in Fig. 5; and this operation is repeated between each particular series of cards being tabulated and recorded.

It is evident that many changes and modifications in the particular construction, combination, and arrangement of the several parts of my improved mechanism for automatically stopping, card tabulating and recording machines, upon the failure of a card to pass beneath the recording and tabulating mechanism herein shown and described may be made, without departing from the scope of my invention.

I claim:—

1. In an apparatus of the character described, the combination of a tabulating mechanism; a feeling device additional to the tabulating mechanism; drive means for said apparatus; and means controllable by said device for bringing said apparatus to rest within one cycle of the apparatus.

2. In an apparatus of the character described, the combination of a tabulating mechanism; a card feeling device additional to the tabulating mechanism; drive means for said apparatus; and means controllable by said device and adapted to bring said apparatus to rest within less than one cycle.

3. In an apparatus of the character described, the combination of a tabulating mechanism; a card feeling device additional to the tabulating mechanism; rotary drive means for said apparatus; and an entirely mechanical means controllable by said device and adapted to bring said apparatus to rest within one rotation.

4. In an apparatus of the character described, the combination of a tabulating mechanism; a card feeling device additional

105

100

110

120

125

130

- to the tabulating mechanism; rotary drive means for said apparatus; and an entirely mechanical means controllable by said device and adapted to bring said apparatus 5 to rest within less than one rotation of the drive means.
5. In a mechanism of the character described, the combination of a drive member; a driven member; an engagement member 10 movable angularly on and relative to the driven member; a trip-member movable independently of the drive member and adapted to engage said engagement member and retract it from the drive member; and additional means engageable by the engagement member to stop the driven member.
6. In a mechanism of the character described, the combination of a drive member; a driven member; an engagement member rotatable on and relative to the driven member and adapted to engage and be moved by the drive member; said driven and engagement members having connection with each other whereby when the engagement 20 member is rotated, it is withdrawn from the drive member; a trip-member movable relative to the driven member and adapted to engage and rotate said engagement member and thereby retract it from the drive member; and fixed means engageable by the engagement member to stop the driven member.
7. In a mechanism of the character described, the combination of a drive member; a rotatable driven member; an engagement member rotatable on the driven member on an axis out of axial coincidence with the axis of the driven member and adapted to engage and be moved by the drive member; 30 said driven and engagement members having cam connection with each other whereby when the engagement member is rotated, it is withdrawn from the drive member; a trip-member movable into and out of engagement with the engagement member and adapted to engage and rotate said engagement member and thereby retract it from the drive member; and additional braking means engageable by said engagement member when retracted.
8. In a mechanism of the character described, the combination of a drive member; a driven member; an engagement member rotatable on the driven member on an axis out of axial coincidence with the axis of the driven member and adapted to engage and be moved by the drive member; said driven and engagement members having cam connection with each other whereby when 40 the engagement member is rotated, it is withdrawn from the drive member; a trip-member adapted to engage and rotate said engagement member and thereby retract it from the drive member; means for moving the trip-member into positive engagement with the engagement member; and a fixed braking means engageable by said engagement member when retracted to positively stop the driven member.
9. In a mechanism of the character described, the combination of a rotary drive member; a rotatable driven member; an engagement member movable on the driven member and normally yieldably engaging and moved by the drive member and provided with a spiral shoulder; a shift member fixed on the driven member and engaging said shoulder; a toothed member fixed to the engagement member; a trip-lever having a gear-rack adapted to mesh with the toothed member to retract the engagement member from engagement with the drive member; and means for moving the trip lever into and out of mesh with the tooth member.
10. In a mechanism of the character described, the combination of a drive member; a driven member; an engagement member 70 slideable on said driven member; a spring keeping the engagement member normally in contact with the drive member; a connection between the engagement member and driven member whereby rotation of the engagement member withdraws the engagement member from the drive member; a trip-member adapted to engage with and rotate the engagement member; and means for moving the trip-member into engagement with the engagement member to withdraw the engagement member from the drive member, against the action of said spring to cause a positive braking effect upon the driven member.
11. In a mechanism of the character described, the combination of a drive member; a driven member; an engagement member on the driven member and engaging and moved by the drive member; a trip-member adapted to retract the engagement member from the drive member; yieldable means for moving the trip-member into engagement with the engagement member; detents adapted to lock the trip-member in or out of engagement with the engagement member; and means for actuating the detents to release the trip-lever.
12. In a mechanism of the character described, the combination of a drive member; a driven member; an engagement member on the driven member and engaging the drive member; a trip-member adapted to retract the engagement member from the drive member; a lock member adapted to lock the trip-member against movement away from retracting engagement with the engagement member; and a release member adapted to unlock said lock-member and to force said trip member out of engagement with the engagement member.
13. In a mechanism of the character de- 120

scribed, the combination of a rotary drive member; a driven member; an engagement member on the driven member and engaging and moved by the drive member; a trip-lever adapted to retract the engagement member from the drive member; a lock-lever adapted to lock the trip-lever in engagement with the engagement member; and a release-lever adapted by a single movement 10 to unlock said lock-lever and to force said trip-lever out of engagement with the engagement member.

14. In an apparatus of the character described, the combination of an apparatus 15 comprising a card support adapted for cards as they are successively passed through the apparatus; drive means for said apparatus comprising an entirely mechanical clutch; a single movable member adapted to be stopped by a card on the support and to pass the support when no card is supported on the support; entirely mechanical means adapted for releasing said clutch; and a flexible reciprocating member connected to 25 said mechanical means and actuated by the passage of said movable member when no card is present, for releasing said clutch.

15. In an apparatus of the character described, the combination of an apparatus 30 comprising a card support adapted to be covered by the cards as they are successively passed through the apparatus; drive means for said apparatus comprising a mechanical clutch; a single plunger adapted to pass 35 through said support when no card covers the same; mechanical means adapted for releasing said clutch; and means connected to said mechanical means and actuated by the depression of said plunger, when no card is 40 present, for releasing said clutch and stopping the apparatus.

16. In an apparatus of the character described, the combination of a recording apparatus comprising a card analyzer comprising a card supporting plate having a stop perforation adapted to be covered by the cards as they are successively passed through the apparatus; drive means for said apparatus comprising an entirely mechanical clutch; a single stop plunger reciprocating simultaneously with the coaction of the apparatus and adapted to enter the stop perforation when no card covers the same; entirely mechanical means adapted for releasing said clutch; and a flexible reciprocating member connected to said mechanical means and actuated by the depression of said stop plunger when no card is present 55 for releasing said clutch and stopping the apparatus.

17. In an apparatus of the character described, the combination of an apparatus comprising a card support; drive means for said apparatus comprising a mechanical 65 clutch; a single movable member adapted to

engage a card on said support and to pass the support when no card is thereon; and a member actuated by the movable member when no card is present, for releasing said clutch.

18. In an apparatus of the character described, the combination of an apparatus comprising a card support; drive means for said apparatus comprising a clutch; a single movable means adapted to engage a card on 70 said support and to pass the support when no card is thereon; and a flexible reciprocating member actuated by the movable means when no card is present, for releasing said clutch.

19. In a mechanism of the character described, the combination of a rotary drive member; a rotatable driven member; a plunger slideable in the driven member and normally yieldably engaging and moved by 85 the drive member and provided with a spiral slot; a shift member fixed on the driven member and engaging in said slot; a pinion fixed to the plunger; and a trip-lever having a gear-rack adapted to be moved 90 into and out of mesh with the pinion.

20. In a mechanism of the character described, the combination of a drive member provided with a throw-lever; a driven member provided with a slide chamber; a plunger slideable in said chamber and provided with a spiral peripheral shift-slot; a spring keeping the plunger normally in contact with the throw-lever; a shift member fixed in said chamber and engaging in said slot; 100 a pinion fixed to the plunger; a trip-lever having a gear-rack adapted to mesh with the pinion; and means for moving the trip-lever into mesh with the pinion.

21. In a mechanism of the character described, the combination of a drive member; a rotatable driven member; a plunger spirally slideable on said driven member; a spring keeping the plunger normally 110 in contact with the drive member; a trip-member adapted to engage and rotate said plunger; and means for moving the trip-member into engagement with the plunger to withdraw the plunger, from the drive member, against the action of said spring 115 to cause the plunger to exert a drag upon the trip member and a braking effect upon the driven member.

22. In a mechanism of the character described, the combination of a drive member 120 provided with a throw-lever; a driven member provided with a slide chamber; a plunger slideable in said chamber and provided with a spiral peripheral shift-slot; a spring keeping the plunger normally in contact 125 with the throw-lever; a shift member fixed in said chamber and engaging in said slot; a pinion fixed to the plunger; a trip-lever having a gear-rack adapted to mesh with the pinion; and means for moving the trip- 130

lever into mesh with the pinion to withdraw the plunger, from the drive member, against the action of said spring to cause the pinion to exert a drag upon the trip member and a braking effect upon the driven member.

23. In a mechanism of the character described, the combination of a drive member provided with a throw-lever; a driven member provided with a slide chamber; a plunger slidable in said chamber and normally in contact with the throw-lever and provided with a spiral slot; means keeping the plunger normally in contact with the throw-lever; a shift member fixed in the sides of said chamber and engaging in said slot; a pinion secured to the plunger so as to rotate therewith; a trip-lever yieldably moved toward the pinion and having a gear-rack adapted to mesh with the pinion so as to rotate the plunger and withdraw the plunger from contact with the throw-lever; and means adapted to lock the trip-lever out of engagement with the pinion and to permit the latter to mesh with the pinion.

24. In a mechanism, of the character described the combination of a drive shaft; a throw-lever carried by the shaft and rotating therewith; a frame; a driven member rotatably supported by the frame and provided with a slide chamber; a plunger slid- able in said chamber and normally in contact with the throw-lever and provided with a spiral peripheral shift-slot; a spring for keeping the plunger normally in contact with the throw-lever; a shift member fixed in the sides of said chamber and engaging in said slot; a pinion secured to the plunger so as to rotate therewith; a trip-lever having a gear-rack adapted to mesh with the pinion so as to rotate the latter and the plunger and cause the withdrawal of the plunger from contact with the throw-lever; a spring for forcing the trip-lever rack into mesh with the pinion; a bell crank lever

adapted to lock the trip-lever out of engagement with the pinion; a lock lever adapted to lock the trip-lever in mesh with the pinion; a release lever adapted by one movement to unlock said lock-lever and to force said trip-lever out of mesh with the pinion; and means for actuating the bell-crank lever to release the trip-lever to permit the latter to mesh with the pinion.

25. In a mechanism of the character described, the combination of a drive member; a driven member; a plunger slidable in the driven member and normally yieldably engaging and moved by the drive member and provided with a spiral slot; a shift member fixed on the driven member and engaging in said slot; a pinion fixed to the plunger; a trip-lever having a gear-rack adapted to mesh with the pinion; a spring for moving the trip-lever into mesh with the pinion; a detent lever adapted to lock the trip-lever out of engagement with the pinion; and means for actuating the detent lever to release the trip-lever to permit the latter to mesh with the pinion.

26. In a mechanism of the character described, the combination of a drive member; a driven member; a plunger slidable in the driven member and normally yieldably engaging and moved by the drive member and provided with a spiral slot; a shift member fixed on the driven member and engaging in said slot; a pinion fixed to the plunger; a trip-lever having a gear-rack adapted to mesh with the pinion; a lock lever adapted to lock the trip-lever in mesh with the pinion; and a release lever adapted by a single movement to unlock said lock-lever and to force said trip-lever out of mesh with the pinion.
